UNITED STATES PATENT OFFICE

166,984

FISHING LINE SINKER

Ralph E. Lawrence, Sacramento, Calif.

Application April 2, 1951, Serial No. 14,695

Term of patent 7 years

(Cl. D31--4)

To all whom it may concern:

Be it known that I, Ralph E. Lawrence, a citizen of the United States, residing in the city of Sacramento, county of Sacramento, State of California, have invented a new, original, and ornamental Design for a Fishing Line Sinker, of which the following is a specification, reference being had to the accompanying drawing, forming part thereof.

Figure 1 is a top plan view of a fishing line sinker showing my new design; Figure 2 is a rear end view thereof; and Figure 3 is a side view thereof.

I claim:

The ornamental design for a fishing line sinker, substantially as shown.

RALPH E. LAWRENCE.
